TRAFFIC GATE

John Conrad Stafford, Steubenville, Ohio

Application January 10, 1949, Serial No. 70,119

2 Claims. (Cl. 39—92)

1

The present invention relates to traffic gates and particularly to improvements in the Traffic Control Gate disclosed in Patent 2,137,193 issued to me on November 15, 1938.

I have found that traffic gates of the type disclosed in the above identified patent involve conditions dangerous to the traffic controlled and the operator of the gate since they provide no means to safeguard against accidental or unintended dropping of the barrier or injury to the operator during operation of the barrier.

Accordingly, it is a primary object of the invention to provide a traffic gate of the kind disclosed in the aforesaid patent by providing safeguards for locking the barrier and shielding parts which may cause injury to the operator.

Another object of the invention is to provide a traffic gate of the aforesaid character having means for positively locking the barrier in its raised position.

Still another object of the invention is to provide guard elements disposed so as to minimize the danger of injury in the open jaw between the descending barrier bearer and its support.

A further object of the invention is to provide a guard element at the handle part of the gate to protect the hands gripping the handle from injury.

Other objects and advantages of the invention will become apparent as the description progresses.

In the accompanying drawing which discloses a preferred example of the invention:

Figure 1 is a top plan view of the gate in operative position with the outer parts of the barrier slats broken away.

Figure 2 is a side elevational view of the same with the gate shown in inoperative raised position in broken lines and one of the guard plates partly broken away.

Figure 3 is an end elevation looking along line 3—3 of Figure 1.

Figure 4 is a vertical section taken on line 4—4 of Figure 1, and

Figure 5 is a side elevational view of the support section of the gate.

Referring to the drawing, wherein like reference characters designate corresponding parts throughout, 10 generally designates the support section of the gate. This section embodies a cylindrical normally vertical socket 11 designed to be rotatably fitted on the upper part of an upstanding post, mounted, for example, in a position near the intersection of two streets, and

removably held on the post by set screws 12 adapted to engage an annular groove in the post. At the upper end of socket 11 is a constricted neck 13 on the exterior of which is a horizontally protruding lug 14 provided with a threaded opening 15 and in which is fitted a vertically adjustable screw 16. Above neck 13 is formed a channel shaped bed 17, the side walls 18 of which are prolonged to provide a pair of parallel horizontally elongated vertical ears 19.

On support section 10 is mounted a bearer section 25 embodying a tubular body 26 connected, by means of a pivot pin 27 extended therethrough and through openings 28, to the ears 19. Fixed to opposed sides of body 26 are a pair of upstanding corresponding sockets 29 in the form of flat hollow wings of rectangular configuration having their outer ends open and terminating in a plane coincident with the outer open end of the body. The outer side wall of each socket 29 has a large opening 30 formed therein. A U-shaped rib 31 joining the inner walls of the wing socket with body 26 advantageously reinforces their connection. The wing sockets receive therein the inner end parts of a pair of barrier slats 32 so that the slats are parallel with the axis of the tubular body.

To the outer bottom marginal wall part of each wing socket 29 is secured, as by machine screws 33, a guard panel 34 embodying a rectangular rigid plate depending from the socket and of such size as to close the sides of the open jaw between the top of bed 17 and the bottom of tubular body 26 when section 25 is swung upward to raise the barrier. Thus, the plates serve to protect the operator and others in close proximity to the gate from injury when the barrier is lowered.

The means for locking the barrier in raised position comprise a locking member carried on the bearer section 25 and cooperable with the ears of the support section to assume resiliently biased manually releasable locking position. In the embodiment illustrated the locking member is in the form of a T-bar 36 having, at the inner end of a body stem 37, a tubular cross element 38 fitted transversely between the sockets 29 and pivotally attached thereto by a bolt 39 extended through tubular element 38 and openings in the barrier slats 32 to also fasten the latter. At its outer end the T-bar has a longer cross bar 40 extended across the outer rounded ends of ears 19 and held against the ears 19 by a coil spring 41 looped about the fixed socket 11 and under

pivot lugs 42 of the bearer section, as illustrated at Figures 2 and 3.

As shown to advantage at Figure 4, tubular body 26 has secured in its outer end part a shank 43 of a longitudinally projecting operating handle 44, shouldered as at 45, to abut the end of the body. That end of body 26 against which the handle abuts has an annular guard flange 46 to preclude accidental sliding of the hands inward on the handle and pinching the same between the T-bar and the ears or the pivot connection.

To raise the barrier from its approximately horizontal operative traffic controlling position to an elevated inoperative position, the handle 44 is swung downward, as shown in Figure 2, thereby causing cross bar 40 of the T-bar to slide over the semi-circular ends of ears 19. When the barrier bearing section 25 attains its completely raised position cross bar 40 will reach a position at the undersides of ears 19 and firmly lock the bearer against downward movement. To release the bearer section for lowering the barrier the operator initially pulls the free end of the T-bar toward the handle and against the tension of spring 41, freeing cross bar 40 of its locking action.

By such automatic locking of the bearer with relation to the support section of the gate accidental or unintended dropping of the barrier and its attendant danger is positively avoided. The panels 34 and flange 46 provide effective safeguards against the pinching of the hands or other parts during movement of the barrier.

It will be obvious to those skilled in the art that various changes may be made in the invention without departing from the spirit and scope thereof and therefore the invention is not

limited to that which is shown in the drawing and described in the specification but only as indicated in the appended claims.

Having thus described my invention, I claim:

- 5 1. In a traffic gate having a support member provided with a pair of spaced apart ears, a barrier bearing member pivotally connected to said ears for swinging a barrier from substantially horizontal to upraised position and return, and a spring biased locking element pivotally mounted on the bearing member and engaging said ears to automatically lock the bearing member when the barrier is raised to its extreme upward position.
- 10 15 2. A traffic gate as claimed in claim 1 wherein said locking element is caused to slide upon curved end parts of said ears by the tension of a manually releasable spring attached to said element and looped about said support member.

JOHN CONRAD STAFFORD.
